UNITED STATES PATENT OFFICE.

JAMES M. TEAHEN AND WILLIAM TAYLOR, OF DETROIT, MICHIGAN; SAID TAYLOR
ASSIGNOR TO SAID TEAHEN.

WATER-CLOSET.

Application filed May 25, 1925. Serial No. 32,845.

The invention relates to water closets of that type in which the tank and bowl are integral and the requisite velocity for flushing is secured by siphonic action. Our prior 5 Patent No. 1,419,328, of June 13, 1922, shows a closet of this type without specific reference to the accessory fittings. The present invention relates to the combination with such general structure of accessories, comprising, first, means for providing a rim flush for the bowl; second, for supplying water to the tank and rim flush operable under varying conditions and complying with rules for sanitary regulation, and; third, various other features as more fully hereinafter set forth.

In the drawings:

Figure 1 is a central longitudinal section through the water closet.

20 Figure 2 is a plan view thereof with the tank cover removed.

Figure 3 is an enlarged section through a portion of the tank and fittings.

25 Figure 4 is a sectional elevation at right angles to Figure 3.

Figure 5 is an enlarged view of a portion of Figure 4.

Figure 6 is a section similar to Figure 3 showing a modified construction.

30 In general construction A is the closet bowl provided with a siphonic action outlet comprising the upwardly extending leg B, the return-bend C, the downwardly extending leg D and laterally extending passage

35 E terminating in a downturned connection F to the soil pipe. G is the tank, which is integral with the bowl and is arranged to the rear and at the sides thereof, its bottom H being slightly above the level of the water

40 seal in the bowl and trap. I is a passage formed in an integral portion of the bowl and tank for conducting water from the latter to the flushing aperture J, which is located below the normal water seal and dis-

45 charges water into the bowl in a tangential direction. K is an overflow passage connecting with the passage I and extending upward in the tank to above the normal water level therein. L is a hollow rim at the top 50 of the bowl having discharge apertures M

for directing streams against the sides of the bowl.

With the structure as thus far described, when water held in the tank is discharged through the passage I and port J into the 55 bowl, it will raise the level therein sufficiently to start siphonic action. This will cause the very rapid discharge of water from the bowl, producing the requisite flushing action. It is, however, necessary to provide 60 for refilling the tank and bowl by means complying with all of the requirements of sanitary regulation. One rule which has been adopted by certain communities prohibits the use of an unvented water supply 65 connection which is in direct communication with the bowl below the overflow level thereof. The reason underlying the rule is that where the water mains are shut off, there may arise a suction due to siphonic action, 70 which in case of a leaky valve in the supply connection of the closet together with the stoppage in the drain connection from the bowl might draw water back into the main to contaminate the same. While this is a 75 most unusual combination of conditions, safety requires the observance of the rule and I have therefore devised a construction which complies with the same. On the other hand, it is equally important that the closet 80 should be noiseless, which necessitates preventing the suction of air through any vent connection. Such result is accomplished by 85 the following construction:

N is the water supply connection, which 85 enters from the bottom H of the tank and extends upward therein. O is a valve fitting at the upper end of the conduit N containing the valve P, or so-called ball cock, which fitting extends upward to a point above the 90 overflow level for the bowl, being open at its upper end for the outward passage of the valve stem which is connected to a lever Q passing through a slotted bearing therein. The lever is fulcrumed at one end to a bifurcated arm R and connected at its opposite end by a link S to a lever T fulcrumed in a bifurcated arm U, which also forms a guide for the lever Q. The lever T has an extension T' connected with the float ball T'. 100

The fitting O is connected to a downwardly extending conduit or hush tube V, which conducts the water to the lower portion of the tank, thereby avoiding noise in refilling. The connection to this conduit is not, however, at the level of the valve seat, but is through a lateral extension O' of the upper portion of the fitting located above the overflow level. This extension O' has a second passage V' therein which leads to the hollow rim L, and a partition O² separating the passage V' from the passage V rises to a point still higher than the connection between the passage V and the fitting O. Thus the water discharged when the valve is lifted from its seat must pass above the overflow level before it can enter the hush tube V, and to a still higher level before entering the rim flush L. Thus when the valve is approaching its seat and the amount of water discharged is small, this entire amount may pass by way of the hush tube instead of through the rim, but when the valve is wider open, water will pass through both hush tube and rim. The proportion between these amounts may be regulated by a valve W, preferably a screw plug having an inwardly extending vain W', which when turned will variably restrict the passage to the hush tube V.

To comply with the requirement that the water supply connection must be vented, the fitting O is provided with a laterally extending passage O³ adjacent to its seat, which then extends upward to slightly above the overflow level and connects with the laterally extending discharge nozzle O⁴. This passage is so proportioned to the other discharge passages and the nozzle O⁴ is so located in elevation that during the normal operation, water will be discharged through the nozzle O⁴ as well as through the other passages. However, in case of any suction in the supply line, the passage O³ and nozzle O⁴ will constitute an air vent, admitting air to the valve seat before any siphonic action can be exerted through the hush tube V or passage V' to the rim.

With the construction as thus far described, assuming the tank to be empty and the valve P to be full open by the dropping of the float T², the water passing the valve will be discharged through all of the several passages described. Thus a small portion will pass outward through the passage O³ and nozzle O⁴. Another portion will be discharged through the hush tube V while a third portion is discharged through the passage V' and hollow rim L to flush the walls of the bowl. This action continues until the valve P, due to the rising of the float, cuts down the amount of water discharged, so that there is insufficient supply to rise over the partition O² into the passage P' and the

whole amount is discharged through the hush tube V and nozzle O⁴. Inasmuch as the amount of water discharged is dependent on the pressure on the line as well as the degree of opening of the valve, the regulating valve W may be adjusted so as to obtain satisfactory operation in any particular locality where the closet is installed. The cutting off of the rim flush before the valve is completely closed has the advantage that all the water discharged through the valve when approaching its seat will enter the tank and not directly the closet bowl, where it is free to pass through the trap. Therefore, any tendency for continuous discharge of water with the valve slightly raised from its seat is avoided. Also the fact that water will discharge through the nozzle O⁴ as long as it is discharging through the hush tube V prevents any sucking of air in through this nozzle and therefore avoids noise.

Assuming an abnormal condition, in which, first, the drain connection becomes clogged so that the bowl does not siphon and fills to the rim; second, that the valve P does not completely seat and permits a leakage of water therethrough; third, that the main is shut off and siphonic action occurs, tending to draw water back through the leaky valve. Under such conditions the first suction upon the water in the fitting O will draw in air through the nozzle O⁴, lowering the level in the portion of the fitting O before there is any discharge from the higher level portion O'. As soon as the air reaches the valve seat all further suction of water is prevented so that under no condition can water in the bowl or the body of the tank be drawn backward into the main. While the nozzle O⁴ operates in this manner under these abnormal conditions, it does not permit the introduction of air in the normal operation of the device as the pressure of water within the fitting O tends to discharge a portion outward through this nozzle instead of drawing air inward.

The discharge of water from the tank G into the bowl is controlled by a flushing valve X, preferably a hollow rubber ball engaging a seat fitting Y. The fitting Y is in the form of an annulus having a depending flange Y' engaging the aperture in the bottom H of the tank, which connects with the passage I and a gasket Y² surrounding the flange Y' forms the seal. The seat Y is secured in position by clamping bolts Y³ engaging ears on diametrically opposite sides of the fitting and passing through apertures in the bottom H. Clamping nuts Y⁴ engage the threaded ends of the bolts, and washers Y⁵ and sealing gaskets Y⁶ are between the same and the apertured bottom. The fitting Y is further provided with an upwardly projecting arm Y' which extends over the

center of the float ball, terminating in guide bearings Y^s for the stem X' of the float ball X .

The operating means for the flush valve 5 comprises a single lever Z , which is fulcrumed upon a pivot pin Z' upon a depending arm Z^2 clamped to the inner side wall of the tank by a shouldered bushing Z^3 passing through an aperture in said wall and a 10 clamping nut Z^4 engaging a threaded portion of said bushing. Through this bushing is passed a rock shaft Z^5 having at its outer end a rocker handle Z^6 and at its inner end the crank arm Z^7 having a hook Z^8 15 engaging the apertured end of a link Z^9 . This link passes through an apertured socket Z^{10} in the lever Z and is headed to form a universal pivotal engagement with said socket. The free end of the lever Z has a loop Z^{11} 20 surrounding the stem X' with a relatively large clearance and engaging a looped head X^2 at the upper end of said stem.

The parts just described, when assembled, 25 normally hold the lever Z with its loop Z^{11} surrounding the stem X' between the guides Y^s and the loop head X^2 . The rocking of the handle Z^6 in either direction will rock the crank arm Z^7 and through the hook Z^8 and link Z^9 will lift the lever Z . This by 30 engaging the loop Z^{11} with the loop head X^2 will pull upward the stem X' and lift the valve X from its seat. As soon as the operating handle is released, it, and the parts connected therewith, will return to normal 35 position, in which the loop Z^{11} will be out of contact with the stem X' so that there is no lateral pressure upon said stem to interfere with its free sliding in the guide bearings Y^s . Therefore, as soon as the water level in 40 the tank lowers, the float ball X will move downward therewith until it again comes in sealing engagement with the seat Y . The rocking movement of the lever Z and its actuating handle Z^6 is limited by a stop Z^{12} 45 at the inner end of said lever, which comes in contact with the depending arm Z^2 . This prevents the lifting of the stem X' higher than necessary for sufficient angular movement of the lever to contact the same with 50 the side of the stem.

In the modified construction shown in Figure 6 instead of the constantly open nozzle O^s I have introduced a check valve O^s 55 preferably a ball which normally drops away from its seat O^s and rests upon a stop O^s thereby maintaining the vent normally open. However, when the valve P is open and the tank is refilling, the ball O^s will close against its seat and remain closed until 60 the water pressure drops below that required to support the ball. The ball will then again drop away from its seat to leave the open vent. This construction prevents discharge of water through the nozzle O^s during 65 the period in which the tank is being re-

filled through the hush tube V but does not in any way interfere with the normal venting or under conditions of reduced pressure.

One very important advantage of the construction is that in case of stoppage in the 70 soil pipe it is impossible to overflow the bowl by repeated operations of the flushing valve. With closets where the tank is placed at a higher level than the bowl this may and frequently does occur for after each flushing 75 the tank refills with water and if at a higher level will overflow the rim of the bowl as soon as the latter has reached its capacity. Such an effect is impossible with the present construction for the level at which the float 80 will close the water supply to the tank is below the rim of the bowl. Thus the height of water in the bowl can never be higher than in the tank and consequently it will be impossible to open the water supply connection 85 when the bowl is nearly full.

What we claim as our invention is:

1. In a water closet, the combination with a siphonic action bowl, a flushing tank and means for introducing water from said tank 90 into the lower portion of the bowl to establish siphonic action, of a rim flush for washing the sides of the bowl, a water supply connection for filling the tank, and means operating during the flushing of the bowl 95 and filling of the tank for supplying water from said water connection to said rim flush.

2. In a water closet, the combination with a siphonic action bowl, of a flushing tank, a connection between said flushing tank and 100 bowl entering the latter beneath the normal water seal, a rim flush for washing the walls of the bowl, and means other than the water in said tank for supplying water to said rim flush during the flushing of the bowl. 105

3. In a water closet, the combination with a siphonic action bowl, of a flushing tank for forming a gravity head between the water seal and the top of the bowl, means for discharging water from said tank into 110 the lower portion of the bowl to establish siphonic action, a rim flush for washing the walls of the bowl, a water supply connection for filling said tank, a float operated valve controlling said water supply connection, 115 and means for diverting a portion of the water to said rim flush when said valve is sufficiently open and for cutting off the supply to the rim flush in advance of the complete closing of the valve. 120

4. In a water closet, the combination with a siphonic action bowl, of a flush tank for forming a gravity head between the water seal and the top of the bowl, means for discharging water from said tank into the 125 lower portion of the bowl to establish siphonic action, a rim flush for washing the walls of the bowl, a water supply connection for filling said tank, and adjustable means for diverting a portion of the water 130

supply to said rim flush under varying conditions of pressure in the supply.

5. In a water closet, the combination with a siphonic action bowl, of a flush tank for forming a gravity head between the water seal and the top of the bowl, means for discharging water from said tank into the lower portion of the bowl to establish siphonic action, a rim flush for washing the walls 10 of the bowl, a water supply connection for filling said tank, having its main discharge outlet extending below the overflow level for said tank and bowl, and means for preventing siphoning back into the supply under 15 any condition.

6. In a water closet, the combination with a siphonic action bowl, of a flush tank for forming a gravity head between the water seal and the top of the bowl, means for discharging water from said tank into the lower portion of the bowl to establish siphonic action, a rim flush for washing the walls of the bowl, a water supply connection for filling said tank having its main discharge 25 outlet extending below the overflow level for said tank and bowl, and an auxiliary opening above said overflow level constituting a siphon breaker in case of suction in the supply line.

30 7. In a water closet, the combination with a siphonic action bowl, of a flush tank for forming a gravity head between the water seal and the top of the bowl, means for discharging water from said tank into the lower portion of the bowl to establish siphonic action, a rim flush for washing the walls of the bowl, a water supply connection for filling said tank having its main discharge outlet extending below the overflow level for 35 said tank and bowl, an auxiliary opening above said overflow level, and means for preventing suction of air through said opening whenever the pressure of the supply is above atmosphere.

45 8. In a water closet, the combination with a siphonic action bowl, of a flush tank for forming a gravity head between the water seal and the top of the bowl, means for discharging water from said tank into the lower portion of the bowl to establish siphonic action, a rim flush for washing the walls of the bowl, a water supply connection for 50 refilling said tank, a float operated valve controlling said water supply and located 55 below the overflow level of the tank, a main discharge passage extending from said valve to a point above the overflow level and then downward to below said level, and an auxiliary conduit extending from said valve to 60 a point above the overflow level.

9. In a water closet, the combination with a siphonic action bowl, of a flush tank for forming a gravity head between the water seal and the top of the bowl, means for discharging water from said tank into the lower 65

portion of the bowl to establish siphonic action, an overflow connection from said tank to said bowl below the overflow level of the rim of the bowl and a water supply connection for filling the tank having a discharge 70 conduit therefrom rising to above the overflow level of the bowl.

10. In a water closet, the combination with a siphonic action bowl, of a flush tank for forming a gravity head between the water 75 seal and the top of the bowl, means for discharging water from said tank into the lower portion of the bowl to establish siphonic action, an overflow connection from said tank to said bowl below the overflow level of the 80 rim of the bowl, of a water supply connection for filling the tank, having a discharge conduit rising to above the overflow level of the bowl normally open to the atmosphere, and a rim flush supplied with water therefrom.

11. In a water closet, the combination with a siphonic action bowl, of a flush tank for forming a gravity head between the water seal and the top of the bowl, means for discharging water from said tank into the lower portion of the bowl to establish siphonic action, an overflow connection from said tank to said bowl below the overflow level of the rim of the bowl, a water supply connection 90 for filling the tank having a discharge conduit rising to above the overflow level of the bowl and being normally open to the atmosphere, and branch extensions of said conduit leading respectively to the rim flush and to 100 a hush tube extending downward in the tank.

12. In a water closet, the combination with a siphonic action bowl, of a flushing tank for forming a gravity head between the water seal and the top of the bowl, means for discharging water from said tank into the lower portion of the bowl to establish siphonic action, a rim flush for washing the walls of the bowl, a water supply connection for filling said tank having its main discharge outlet extending below the overflow level of said tank and bowl, a conduit leading from said discharge outlet to a point above the overflow level of said tank and bowl forming a normally open vent preventing siphoning and a normally open check valve in said conduit adapted to close said vent during the discharge of water into said tank.

13. In a water closet, the combination with a siphonic action bowl, of a flush tank for forming a gravity head between the water seal and the top of the bowl, means for discharging the water from said tank into the lower portion of the bowl to establish siphonic action, a rim flush for washing the walls of the bowl, a water supply connection for filling said tank having its main discharge outlet extending below the overflow level of said tank and bowl, a conduit rising 130

from said main discharge outlet to above the overflow level of said tank and bowl and an upwardly seating ball check valve in said conduit forming a normally open vent which is closed only during the filling of the tank.

14. In a water closet, the combination with a siphonic action bowl, of a flushing tank for forming a gravity head between the water seal and top of the bowl, means for dis-
¹⁰ charging water from said tank into the lower

portion of the bowl to establish siphonic action, a water supply connection for filling said tank and means for closing and maintaining closed said water supply connection before the level in said tank can reach the 15 level of the rim of the bowl.

In testimony whereof we affix our signatures.

JAMES M. TEAHEN.
WILLIAM TAYLOR.
